Patented Sept. 16, 1919.

INVENTOR.

W. C. Toll,

By J. Edward Maybee.

ATTOR.

UNITED STATES PATENT OFFICE.

WILLIAM CLAIR TOLL, OF SIMCOE, ONTARIO, CANADA.

TONSILLOTOME.

1,316,003.

Specification of Letters Patent. Patented Sept. 16, 1919.

Application filed May 21, 1919. Serial No. 298,751.

To all whom it may concern:

Be it known that I, WILLIAM CLAIR TOLL, a resident of the town of Simcoe, in the county of Norfolk, Province of Ontario, 5 Canada, physician, have invented certain new and useful Improvements in Tonsillotomes, of which the following is a specification.

This invention relates to instruments for 10 removing tonsils, and my object is to devise an instrument which will remove tonsils in their entirety without injury or danger to surrounding anatomical structures and with a minimum of hemorrhage.

15 I attain my object by means of the constructions illustrated in the accompanying drawings in which—

Figure 1 is a plan view of the device showing the half rings of the hemostat open;

20 Fig. 2 a similar view showing the half rings closed;

Fig. 3 a side elevation showing the half rings closed; and

Fig. 4 an end view of the half rings and 25 the semi-annual knife.

In the drawings like numerals of reference indicate corresponding parts in the different figures.

The hemostat comprises two half rings G, 30 which are formed on or connected to the ends of bars H. These bars are provided with hinge knuckles A B, by means of which they are hinged together. The hinge pin is preferably formed by the handle C of 35 the knife D. This knife is of semi-annual form, as shown, and when rotated moves in shear fashion past the inner faces of the half rings G. The outer ends of the jaws are preferably halved together as shown and provided with a pivot F in alinement with the 40 handle C. The knife also preferably engages this pivot F and is thus supported at its outer end. The other ends of the bars H are preferably bent up to form handles 45 E. The end I of one handle is extended to form a resilient tongue adapted to be snapped into a keeper J formed on the end of the other handle. The bars H may thus be locked to retain the half rings G in the position shown in Figs. 2, 3 and 4. It will be 50 noted that when the half rings are opened out as shown in Fig. 1 that a completely unobstructed fenestrum is formed through which the tonsil to be removed may protrude when the device is positioned for use.

The device is used in the following manner: In the first place the instrument is opened as shown in Fig. 1 and by suitable manipulation the tonsil to be removed is forced into or through the half rings, which 60 are then folded together and locked. This procedure separates the tonsil from both the anterior and posterior faucial pillars and the superior constrictor pharyngeal muscle and crushes the connecting tissues, thereby 65 securing hemostasis. The knife is then rotated by means of its handle to remove the tonsil from the crushed stump.

With my instrument it will be found very much easier to completely remove the tonsil 70 without excessive hemorrhage than with the devices at present employed for this purpose.

What I claim as my invention is:—

1. In a tonsillotome, the combination of a pair of substantially parallel bars hinged together and each having a half ring formed at one end, said half-rings being adapted to coöperate to form a hemostat and when open to form an unobstructed fenestrum. 75

2. In a tonsillotome, the combination of a pair of substantially parallel bars hinged together and each having a half ring formed at one end, said half-rings being adapted to coöperate to form a hemostat; and a semi-annual knife journaled concentric with the 85 hinges of the aforesaid bars adapted to separate a tonsil from a crushed stump grasped by the half rings. 80

3. In a tonsillotome, the combination of a pair of substantially parallel bars hinged together and each having a half ring formed at one end, said half-rings being adapted to coöperate to form a hemostat, bent handles on said bars; and means for releasably locking said handles together with the half rings 95 in coöperative position. 90

4. A tonsillotome according to claim 2 in which the knife is provided with an operating handle which forms also a hinge pin for the hinges of the bars carrying the half 100 rings.

Signed at Simcoe this 16th day of May, 1919.

WILLIAM CLAIR TOLL.
